SHIRT COLLAR SUPPORT

William R. Kohl, Glenview, and Arden L. Iverson,
Chicago, Ill., assignors to Para-Lux Products
Company, Chicago, Ill., a corporation of Illinois

Application August 13, 1947, Serial No. 768,305

6 Claims. (Cl. 223—83)

1

This invention pertains to a collar or neckband support or protector for a collar-attached shirt, adapted to protect a new or freshly laundered shirt against crushing, crumpling or wrinkling.

It is an object of the invention to provide a very simple, one piece, flexible paperboard collar support characterized by its novel rigidifying and bracing provisions, whereby the support is adapted to sustain considerable vertical crushing load when operatively positioned in the neckband of a shirt.

A further object is to provide a protective support of the foregoing character which is fabricated from a relatively small blank of paperboard stock slitted and creased in a manner to produce an improved, strut-like bracing action in a shirt neckband, together with an effective spring engagement of the support against the inner surface of the shirt neckband.

More specifically, it is an object to provide a support in the form of a paperboard or cardboard element adapted to be folded on one or more lines and bent into an arcuate shape for placement in the shirt neckband, said support when so folded and positioned having a multiply thickness in the zone at which crushing load is applied to the shirt, and further being characterized by a multiple leaf spring expanding spring action into holding engagement with the shirt neckband on either side of said zone.

Yet another object is to provide a paperboard collar or neckband protector of the above description having foldable means adapted to rigidify and stiffen the same in its operative position relative to a shirt neckband and also to act as a locking jaw having frictional, biting engagement with the adjacent inner surface of the neckband to hold the protector in operative position.

The foregoing statements are indicative in a general way of the nature of the invention, but other and more specific objects will be apparent to those skilled in the art upon a full understanding of the construction and operation of the device. Various embodiments of the invention are presented herein for the purpose of exemplification, and it will be appreciated that the invention is susceptible of incorporation in still other modified forms coming equally within the scope of the appended claims.

In the drawings,

Fig. 1 is a plan view of a blank from which the shirt collar support is set up, in accordance with a preferred form of the invention;

Fig. 2 is a plan view of a men's collar-attached

2

shirt, wrapped and having the support of the invention operatively applied thereto to protect the collar thereof;

Fig. 3 is an enlarged fragmentary view in section on a line 3—3 of Fig. 2;

Fig. 4 is a fragmentary view in plan, similar to Fig. 2, illustrating the manner in which the device is foldably manipulated in applying the same to the shirt;

Fig. 5 is a plan view which is generally similar to Fig. 2, illustrating a slightly modified embodiment of the invention including a collar support in combination with a shirt encircling band; and

Figs. 6 and 7 are plan views of blanks from which still further modified embodiments of the support are formed.

Referring to Figs. 1 to 4 of the drawings, wherein a preferred embodiment of the shirt collar support is illustrated, a cardboard sheet 20 of a suitable grade and stiffness is die-cut to provide the blank 10. Said blank includes a body portion 11 having a pair of identical, laterally projecting arms 12 extending from either end thereof and, medially and at either side of said arms, the opposed flexible reinforcing and locking panels or tabs 13 and 14. The tab 13 projects a relatively slight distance from the main body 11 of the blank and is provided with a series of serrated teeth 15 along its free edge.

Said tab 13 is flexibly conjoined to the body 11 by a curved line of slits 16 which, in general, parallel the adjacent sides of the arms 12, but are spaced inwardly therefrom to a slight extent. The slits are located only in the area of the body 11 between the sides of tab 13 and extend entirely through the material of the blank to, in effect, define an obtusely angled fold line about which tab 13 is bendable relative to the body 11 and arms 12. It should be noted that the central slit 16 has an arcuate portion which serves to define a slight tongue-like projection 17 on body 11, cut out of the material of the tab 13. The sides of said last named tab are caused to extend into the body 11, i. e., beyond the sides of arms 12, by the slits 16 at either side of the tab which intersect the arms and extend inward as far as the slits 16, whereby the tab 13 may be readily bent along the line of the slits.

The tab 14 on the opposite side of the body of the blank extends substantially in a lateral direction from said body, being outlined by the angular, convergent edges 19 and a serrated edged, external tongue 20 of T-shape. Said tongue is partially separated from tab 14 by the curved slits 21 which extend inwardly from the

tab edges 19 to outline the arms of the T-shaped tongue, plus the convergent lines of serrated slits 22 in the body portion of tab 14. These slits 22 join the ends of slits 21 and at their opposite ends terminate in out-turned portions 23.

Like the tab 13, tab 14 is adapted to be folded relative to the body 11 and arms 12, and for this purpose is provided with the two straight, angularly disposed slits 24 through the material of the blank. Said slits 24 are substantially spaced from one another at their adjacent ends and are also spaced at their outer ends from the short slits 25, similar to slits 18, cut into the blank at the juncture of the body and arms thereof.

The tongue 20 which, as illustrated in Figs. 2 and 3, is disposed externally of and overlies the lapels or collar flaps 26 of the collar-attached shirt 27 when the support is applied to the latter, may receive suitable advertising or decorative material.

In use, the operator bendably deflects tabs 13 and 14 in the same direction relative to the body panel 11, to overlie the same on one side, and then curves the thus folded device in the direction toward the opposite side, thereby imparting a convex outline to the tabs and body. Such flexure of the device causes the tabs to be sprung, displaced or biased further towards the body 11 along their respective hinge lines or slits 16, 24, storing up energy in the manner of a multiple leaf spring. With the tongue 20 exposed outwardly and upwardly, the user now grasps the device, with his thumbs on the areas of tab 14 at either side of the serrated line 22, and positions the arms 12, body 11 and tabs 13, 14 inside the neck band of the shirt, in conformity with the contour of the neckband, the projection 17 engaging the rear of the shirt. He then releases the arms, allowing the support to expand and engage the neck band around a considerable length of the latter. In positioning the device, care is taken that the tongue 20 overlies the collar lapels 26 and that the collar opening at the front or throat is properly seated in the slit termini 23.

When so positioned, the tabs 13, 14 of the device serve to reenforce and stiffen the support against vertical crushing load, particularly at the front of the neckband where it is most damaging. At the same time the tabs contribute a substantial multiple-leaf spring flexing action which is very effective in maintaining engagement of the protective support with the internal surface of the neckband. The protector is further braced and held in place against inadvertent upward displacement by the upward biting action of the serrated teeth 15 of tab 13 against the neckband. The engagement of the slits 23 with the top of the neckband adjacent the collar opening furthers resistance to displacement.

It will be appreciated that these multiple bracing and locking actions are very effective in preventing loss of the protector from the collar in either direction; yet to remove the protector it is only necessary to grasp one or both of the arms 12 and swing the same internally and upwardly. The dual tab feature in effect constitutes a relatively stiff vertical truss for the protector and imparts a multiple-leaf spring action which maintains close engagement with the collarband, so that loss of this truss action is not likely.

The tongue 20 extends over the front of the collar lapels, providing a clamping action which holds said lapels in place and additionally aids in protecting the lapels against crumpling and crushing. As illustrated in Fig. 3, the protector

extends above the top of the neckband, particularly at the front of the latter, to afford a buffer of exceptional strength protecting the collar when shirts are stacked one on top of the other, likewise preventing wrapping material from coming into direct contact with the collar.

It is desirable that the ends of the arms 12 be cut on a slant downwardly to terminate in points having frictional engagement with the collar band, and said ends are likewise serrated for increased frictional engagement with the collar band.

The above noted simplicity of insertion and removal of the protector are largely due to the fact that the device involves no parts or elements which need be inserted between the lapels 26 and collar neckband. Such elements are superfluous in the present device in view of its more than adequate strength and rigidity as well as its marked ability to maintain engagement with the collar by reason of the novel spring action which it incorporates.

In Fig. 5 there is illustrated a modified embodiment of the invention, involving the combination of a support and protector of the foregoing type with an elongated relatively wide wrapping band 30. Said band is connected to the remainder of the device in the same manner as the tongue 20 of the above described embodiment and, like the tongue, is adapted to overlie and confine the ends of lapel 26. This form is applied to the neckband in the manner described above, and suitable locking or securing provisions 31 at the ends of the band enable the latter to be releasably located in surrounding relation to the pressed and folded shirt.

Fig. 6 illustrates an embodiment of the invention which is similar in all respects to the form of Figs. 1 through 4, and similarly employed, with certain alterations. For one thing, the tab denoted 13' is bendably connected to the body 11 by means of a central arcuate slit 32 extending entirely through the material of the blank, and cooperating crease lines 33, as distinguished from the slits of the Fig. 4. The opposite tab 34 is bendably connected to the body by alternating, aligned creases 35 and slits 36. In use the tabs 13' and 34 are manipulated in exactly the same fashion as the tabs 13, 14 of the first embodiment and similarly inserted in the neckband opening.

The form illustrated in Fig. 7 is identical to that of Fig. 6 with the exception that the tab 34 is omitted.

In all of the above embodiments a collar support and protector is provided which has very desirable resistance to inadvertent displacement. The upwardly and forwardly projecting tab adjacent the lower edge of the support engages upwardly in the manner of a hook against the collar band to resist withdrawal. Notwithstanding this, said tab does not present any opposition to downward movement of the support into the neckband when the device is being positioned. This feature is of primary importance in the invention. Furthermore, bendable connection of said tab 13 along a non-linear or obtusely angled fold line results in the production of a toggle action at this connection, in the sense that once said tab has been initially bent forwardly and upwardly to a slight degree, the curving of the rearwardly extending arms 12 causes said tab to be further flexed toward the adjacent surface of the collar support. At the same time spring action is stored in the parts and the material of the support placed under stress at the toggle

connection of the tab and support body. The result is a substantial rigidification at the fore-part of the collar area, and a substantial lateral thrust in opposite directions against the neckband to assist the upwardly projecting tab 13 in resisting displacement.

What we claim is:

1. A collar supporting device of the type described, comprising a flexible, sheet like body having integral neckband engaging arms projecting laterally thereof, and a locking and rigidifying flap hingedly connected to said body by a non-rectilinear fold line including separate hinge portions which are spaced substantially from one another lengthwise of said line and bendable into overlying relation to the body, said flap being arcuately flexed with said body and arms into general conformity with a neckband opening for insertion in the latter, with the flap on the convex side of the body, said flap being of sufficient length to laterally over-extend the forward central throat zone of said neckband and being spring-flexed upwardly and further toward said body about said fold line by said arcuate flexure whereby to constitute with said body a rigid, multi-ply bracing strut having a multiple leaf spring expanding and engaging action against the interior of said neckband, the free edge of said flap engaging upwardly against said neckband to lock the device in place therein.

2. A collar protecting device of the type described, comprising a body member of flexible sheet material having integral, laterally projecting neckband engaging arms of substantial length and an integral locking and rigidifying tab between said arms, said tab being connected to said body member by a preformed, non-rectilinear fold line including separate hinge portions which are spaced substantially from one another and being bendable on said line into overlying relation to said body member, said member, arms and tab being arcuately flexed as a unit, with said tab on the convex side thereof, into general conformity with a neckband opening for insertion in the latter, said tab being of sufficient length to laterally over-extend the forward central throat zone of said neckband.

3. A collar protecting device of the type described, comprising a body member of flexible sheet material having integral, laterally projecting neckband engaging arms of substantial length, an integral locking and rigidifying tab between said arms, said tab being connected to said body member by a preformed, obtusely angled fold line and being bendable on said line into overlying relation to said body member, said member, arms and tab being arcuately flexed as a unit, with said tab on the convex side thereof, into general conformity with a neckband opening for insertion in the latter, and a further projecting element integrally connected to said body member in opposed, aligned relation to said tab and bendable toward the latter over said convex surface, said tab being of sufficient length to laterally over-extend the forward central throat zone of said neckband.

4. A collar protector of the type described comprising a central member having a pair of

integrally connected, laterally extending spring arms adapted to be flexed into general conformity with a neckband opening for insertion therein, and a locking and rigidifying flap integrally hinged to said member between said arms and bendable relative thereto, said flap being provided with a roughened free edge and in said bent relation being springably biased toward the surface of said member when the latter is so flexed and conformed, and extending upwardly adjacent said surface for locking engagement of said free edge with an inner neckband surface, said flap being of sufficient length to laterally over-extend the forward central throat zone of said neckband.

5. A collar protector and support comprising a flexible paperboard member having integral oppositely extending arms, said member and arms being adapted to be flexed into general conformity with a neckband opening for insertion and engagement therein, and a pair of opposed flaps disposed in alignment with one another transversely of the direction of said arms and integrally and flexibly connected by preformed fold lines to said member medially of said arms, said flaps extending in opposite directions relative to said member, being foldable toward a common surface of the member and being unidirectionally biased toward said surface when said member is so flexed and conformed, said flaps being of sufficient length to laterally over-extend the forward central throat zone of said neckband.

6. A collar support comprising a flexible elongated member of sheet material adapted to be bent into curved form in general conformity with the neckband of a shirt and to be inserted within said neckband to extend upwardly in bracing relation thereto, said member having a tab bendably connected thereto adjacent the lower side and between the ends thereof, which tab projects forwardly and upwardly from the convex surface of the member in said curved condition thereof for gripping and displacement resisting engagement with said neckband, said tab being of sufficient length to laterally over-extend the forward central throat zone of said neckband, the bendable connection of said tab to said member being constituted by a non-rectilinear fold line therebetween including separate hinge portions which are spaced substantially from one another lengthwise of said line, enabling automatic toggle flexure of the upwardly extending tab toward said convex surface when said member is curved, to thereby store spring energy at said connection.
